US0D1109591S

(12) **United States Design Patent** (10) **Patent No.:** **US D1,109,591 S**
(45) **Date of Patent:** **** Jan. 20, 2026**

(54) **END BRACKET**

(71) Applicant: **Pegasus Solar Inc**, Richmond, CA (US)

(72) Inventor: **Erich Kai Stephan**, Richmond, CA (US)

(73) Assignee: **PEGASUS SOLAR INC**, Richmond, CA (US)

(**) Term: **15 Years**

(21) Appl. No.: **29/957,629**

(22) Filed: **Aug. 14, 2024**

(51) **LOC (15) Cl.** **08-05**

(52) **U.S. Cl.**

USPC **D8/354**

(58) **Field of Classification Search**

USPC D13/102, 118, 184, 199; D8/349, 354,

D8/355, 363, 371, 373

CPC A47B 96/061; A47B 96/06; A47B 96/027;

A47B 96/028; A47B 57/00; A47B

57/045; A47B 57/42
